UNITED STATES PATENT OFFICE.

HENRY W. JOHNS, OF NEW YORK, N. Y.

BOILER OR PIPE COVERING.

SPECIFICATION forming part of Letters Patent No. 433,470, dated August 5, 1890.

Application filed December 12, 1889. Serial No. 333,559. (No model.)

To all whom it may concern:

Be it known that I, HENRY WARD JOHNS, a citizen of the United States, and a resident of New York city, in the county of New York and State of New York, have invented a certain new or useful Boiler or Pipe Covering, of which the following is a specification.

My invention relates to an improvement in boiler or hot pipe non-conducting coverings; and it consists in the peculiar construction of a compound sheet or covering hereinafter described.

The drawing illustrates a vertical section of my improved covering.

I first make a sheet or "board," so called, of cut, picked, or shredded sponge and paper stock, which may be made into sheet or board form by pulping the comminuted sponge and paper-stock in an ordinary paper-maker's apparatus, and then make it into sheet form by any suitable apparatus or in any other preferred manner. The sheet thus produced has certain characteristics which peculiarly adapt it to the described uses—to wit, it is very light, very porous, pliable, bulky in proportion to weight of material, elastic, and inexpensive; but when placed upon surfaces which subject it to a considerable heat the paper-stock, and frequently, also, the sponge will char. Thus the covering soon becomes useless, and in some instances has been known to take fire. In order, therefore, that the peculiarly-valuable qualities of the sponge and paper-stock sheet or board may be utilized without the disadvantages above recited, I

desire, both sides of the said sheet a coating or nap of fibrous asbestos by cementing the same thereto with silicate of soda or other cementing material, preferably, but not necessarily, fire-proof. The resulting fabric is somewhat similar to that which would be produced by attaching a surface layer of lamb's wool to a heavy felt, and is peculiarly well adapted to the uses described.

It will be noticed that in my improved covering the asbestos is permanently attached to the pulp and sponge layer. Thus separation of the fireproofing material from it is impossible, and they may both be applied to the pipe by one and the same operation.

In the drawing, A represents the sheet formed of sponge and paper-stock, and B B' represent the surface-layers of fibrous asbestos, that marked B' being of longer staple than the other. Of course the asbestos may be of such length of fiber as preferred.

I claim—

A compound covering fabric consisting of an integral sheet composed of sponge and paper-stock and a coating of soft open or loose fibrous asbestos, the sponge and paper-stock constituting the body and the asbestos the surface portions of the sheet, substantially as described.

Signed at New York, in the county of New York and State of New York, this 10th day of December, A. D. 1889.

HENRY W. JOHNS.
